REMOTE CONTROLLED SELECTOR SWITCH

Ian David Smith, Vancouver, British Columbia, Canada

Application August 16, 1954, Serial No. 449,935

17 Claims. (Cl. 200—105)

This invention relates to selector units which may be placed at different points or in different machines, all of said units being operated by a single control at a remote point.

This selector unit was primarily designed for use in model railroad engines in order that a plurality of engines may be independently operated on a single track by one control unit. However, it is to be understood that the unit may be used with any type of machinery in order that any of a plurality of machines may be started and shut off by a single control.

The control for this selector unit includes means for selectively creating different numbers of electrical impulses. A single pair of conductors extends to a plurality of selector units, said units being connected in parallel. If the selector units are located in model railroad engines, the rails on which the engines operate form part of the pair of conductors.

Each selector unit includes a carriage and means responsive to the electric impulses for moving the carriage forwardly a predetermined distance for each impulse. Suitable means is provided for returning the carriage to its normal position when the impulses cease. An elongated carrier is mounted near and parallel to the carriage, said carrier having a plurality of spaced shoulders thereon. This carrier is yieldably mounted so that it may be depressed relative to the carriage. The carriage includes means for successively engaging the shoulders as it moves forwardly in response to the electric impulses. Each impulse causes this means to engage a different shoulder. As the carriage starts to move back to its normal position when the impulses cease, the shoulder-engaging means thereof engages the last shoulder with which it came into contact and depresses the carrier.

There is a carrier shoulder in each selector unit for each device to be controlled by this apparatus. If there are three such devices and therefore three selector units, there would be at least three of these shoulders in each unit. There is a control switch within each selector unit mounted adjacent one of the shoulders thereof. Assuming that there are three shoulders, these being numbered 1 to 3, the control switch in one selector unit would be adjacent No. 1 shoulder, the switch in another adjacent No. 2 shoulder, and the switch in the remaining unit adjacent No. 3 shoulder. If it is a model railroad and the operating power is sent over the same conductors as that for the selector units, a blank shoulder may be required, that is, a shoulder without a control switch near it. The control switch is operated when the shoulder adjacent it is engaged by the carriage means and depressed thereby. This control switch is connected to electrical means for doing the required job. For instance, if the selector units are in model engines, the control switch of each engine may start, stop or reverse the electric motor of the engine.

Any desired number of selector units may be set up in a single system. As previously stated, any suitable means may be provided for creating the electric impulses. It has been found, however, that a dial unit of the type used

on automatic telephones is very suitable for this purpose. The ordinary dial unit includes numbers 1 to 10, and such unit may be used for controlling anything up to 10 selector units, but there is no reason why a dial unit with more or less numbers could not be used.

Examples of this invention are illustrated in the accompanying drawings, in which,

Figure 1 is an enlarged side elevation of one form of selector unit,

10 Figure 2 is an elevation of the left end of the unit shown in Figure 1,

Figure 3 is an elevation of the opposite side of the unit to that shown in Figure 1,

15 Figure 4 is a vertical cross section taken on the line 4—4 of Figure 1,

Figures 5 to 8 are fragmentary views illustrating a sequence of movements during the operation of the unit,

Figure 9 illustrates one type of control switch which may be used in the selector unit,

20 Figure 10 is a wiring diagram of a control switch for operating a reversible motor,

Figure 11 diagrammatically illustrates a system incorporating three selector units,

25 Figure 12 is a view similar to Figure 3 of an alternative form of the invention,

Figure 13 is an elevation of the left end of the unit of Figure 12,

Figure 14 is a vertical section taken on the line 14—14 in Figure 12,

30 Figure 15 is a view similar to Figure 3 of still another form of the invention,

Figure 16 is a fragmentary side elevation with the carriage advanced from its normal position and with the carrier depressed, and

35 Figure 17 is a vertical section taken on the line 17—17 of Figure 16.

Referring to Figures 1 to 4 of the drawings, 10 is a selector unit having a flat frame 11 projecting upwardly from a suitable base 12. This frame has a horizontal slot

40 15 spaced a little below its upper edge 16 and extending rearwardly from the forward end 17 of the frame and opening into a large opening 18 formed in said frame adjacent its rearward end 19. A carriage 22 is slidably mounted on the upper edge of the frame. This carriage

45 may be constructed in any desired manner, and in this example, it is made up of side plates 23 and 24 which overlap the opposite faces of the frame and are connected together by a plurality of pins 25 which ride on the upper edge 16 of the frame, and by at least one pin 26 spaced below the other pins and riding in slot 15. A spring 28 extends between the rearward end of the carriage and the rearward end of the frame to retain the carriage in a normal position against a stop 29 adjacent this frame end.

50 A relatively long ratchet arm 31 is pivotally mounted at its lower end 32 on the base 12 and extends upwardly past the side of carriage 22, and has a ratchet pawl 34 pivotally mounted on its upper end, said pawl having a cam 35 formed thereon at its inner end. A spring 37 holds the arm in a normal position with the cam 35 of

60 the pawl bearing against a seat 39 formed in the upper end of a vertical member 40 which is secured to and extends upwardly from frame 11, said member being spaced outwardly from the frame by a block 41, see Figure 4. By referring to Figures 2 and 4, it will be seen that the 65 pawl 34 is located above the upper edge of carriage 22, while the cam 35 thereof extends laterally from the pawl so that it is in line with the member 40. This pawl is adapted to engage a plurality of ratchet teeth 44 formed in the upper edge of the carriage.

70 When arm 31 is in its normal position, the cam 35 of the pawl is seated on the step 39 at which time the free end of the pawl is lifted clear of the carriage. When

the ratchet arm is moved out of its normal position, the pawl drops down and engages one of the ratchet teeth 44, said teeth being so arranged that when the ratchet arm is moved, the pawl moves the carriage with it, and when the ratchet arm returns to its normal position, the pawl rides over the backs of the teeth.

Suitable means is provided for moving the ratchet arm forwardly of the selector unit frame under the influence of electric impulses. This may be accomplished by a solenoid 47 mounted on the side of the frame 11 and having a movable core 48 slidably fitting therein. The outer end of this core is pivotally connected at 49 to the ratchet arm 31. When the solenoid is energized, the core 48 is drawn into it thereby moving the ratchet arm forwardly, and when the solenoid is de-energized, spring 37 returns the ratchet arm to its normal rearward position. Thus, when the solenoid is energized by an electric impulse, the pawl 34 drops down and engages a tooth 44 of carriage 22 to move it forwardly a predetermined distance. If the solenoid is subjected to a series of impulses, the carriage will be moved forwardly a distance equal to the travel of the ratchet arm for each impulse.

Suitable means is provided for preventing the carriage from returning to its normal position while the arm 31 is operating under the action of the electric impulses. For this purpose a plurality of spaced and aligned levers 54 are mounted on the frame 11. Each lever is mounted by means of a pin 55 just below the opening 18 in the frame so that the upper end of the lever overlaps said opening, as clearly shown in Figure 3. Each lever has a shoulder 57 formed in its upper end by a prong 58 projecting upwardly from said end at one side thereof. These shoulders face towards the forward end 17 of the frame. The lower ends of these levers are pivotally connected to a common bar 60, one end of which is connected by a link 61 to the plunger 62 of a dashpot 63. The flow of air into and out of the dashpot is controlled by a plunger 64, the position of which may be adjusted by a set screw 66 which is threaded through a lug 67 extending laterally from the frame 11. The opposite end of bar 60 is connected to a spring 70 which tends to draw the piston towards the open end of the dashpot and one of the levers against a stop pin 71, at which time said levers are in their upright positions. The levers 54, and the portion of bar 60 connecting their lower ends together, form a carrier generally designated by the reference number 72.

There is a lever 54 and, consequently, a shoulder 57 for each selector unit in the system. In the illustrated example, there are three of these levers and for convenience they have been numbered 1, 2 and 3 from the rearward towards the forward end of the frame 11. If the operating current for the engines flows along the same conductor as that for the selector units, an extra lever and shoulder may be required, and in this example the lever has been numbered 0.

A latch 74 is pivotally mounted at 75 on the rearward end of carriage 22 near the bottom thereof and has a finger 76 projecting laterally therefrom. The latch spans the carriage and has a notch 77 in its upper edge so that it may hang downwardly from the carriage. The latch is provided with a weight 79 which tends to swing it into a vertical position and also acts as a bearing surface since it is in line with the prongs 58 of the levers 54. A lug 81 projects upwardly from the latch on one side of the carriage and is engaged by the stop 29 when said carriage is in its normal at-rest position. At this time, the lug is moved forwardly so that the latch is moved rearwardly into an inclined plane, as clearly shown in Figure 3. A stop 83 projects downwardly from the carriage to prevent the latch from swinging forwardly beyond a vertical plane.

A control switch 87 of any desired construction is mounted on the base 12 adjacent one of the levers 54 for operation therewith. In this example, the switch consists of a rotor 89 having a plurality of spaced lugs 90

projecting outwardly from a side thereof and arranged around its periphery. The rotor is mounted on the side of frame 11 opposite that on which the levers are mounted. The rotor switch is of such type that when one of the lugs 90 is engaged and moved around the centre of the rotor a predetermined distance, the rotor automatically moves on to a new position. Each lug represents a switch position. If the selector unit is used in a model railroad engine, the various switch positions may alternately turn the engine motor on or off, or they may in sequence start the engine ahead, stop it, and reverse it. In this example, there are four lugs 90 and for convenience they have been labelled A to D.

The control switch 87 is positioned in the illustrated form of the invention to operate with lever No. 2, in which case one of the lugs 90 of the switch rotor is always aligned with the outer end of the lever by the shoulder thereof. In Figures 3, 5 and 6, the lug A is beside the lever shoulder. For the purpose of illustration, the various positions of the control switch are as follows:

- A—stop
- B—ahead
- C—stop
- D—reverse

During operation, each electric impulse causes carriage 22 to be moved forwardly sufficiently to permit the latch 74 to engage the next lever shoulder in line. If there is a No. 0 lever, the first impulse has no effect in operating the equipment under control, but this impulse causes the latch to engage the shoulder of No. 0 lever. The next impulse causes the latch to engage the shoulder of lever No. 1, the following impulse causes it to rest on the step of No. 2 lever, and so on. When the ratchet arm 31 is being returned to its normal position by spring 37 after an impulse, spring 28 tends to return the carriage to its normal rearward position. However, the latch bears against the shoulder 57 of a lever after an impulse so that said spring has to pivot or depress the upper end of the lever against the action of spring 70 and dashpot 63. In other words, the upper portion of carrier 72 is depressed at this time. Thus, the return movement of the carriage is relatively slow so that it cannot return to its normal position during a series of impulses. When the impulses cease, the carriage is drawn rearwardly, at which time the latch depresses the carrier lever with which it is in engagement until the former reaches substantially a vertical position, after which the latch is moved clear of the lever shoulder. The return of the carrier levers to their normal upright positions is slowed down by the dashpot, thus, the carriage is able to move back to its normal position against stop 29.

As previously stated, the control switch 87 is so located that there is always one of its lugs 90 aligned with the shoulder 57 of lever No. 2. Figures 5 to 8 illustrate the sequence of movement during operation of the switch. When the solenoid 47 receives three consecutive electric impulses (the purpose of the first impulse merely being to get over lever No. 0), the latch 74 is moved over until it engages the shoulder of lever No. 2. In Figure 5, carriage 22 is moving forwardly and the latch is just about to drop down on to the lever end from the prong thereof. Figure 6 shows the latch on the lever end and against shoulder 57, at which time latch finger 76 engages lug A of the switch. The rearward movement of the carriage under influence of spring 28 depresses the carrier lever and at the same time causes rotor 89 to be turned sufficiently to force lug A on to the next switch position. This leaves lug B in the position just vacated by lug A. During this time, the latch 74 swings downwardly to a vertical position where it is retained by stop 83, see Figure 7. Further rearward movement of the carriage moves the latch clear of the lever shoulder so that the lever is free to return to its normal position. 75 As the dashpot prevents the carrier or levers from return-

ing to their vertical positions too rapidly, the latch will move over levers Nos. 1 and 0 respectively without difficulty. Thus, when the solenoid is subjected to three consecutive impulses, this particular selector unit moves its control switch into a new position.

If the solenoid is subjected to four electric impulses, latch 74 is moved over until it engages the shoulder of lever No. 3. This lever is depressed in the manner described above in connection with lever No. 2, but finger 76 is clear of the control switch. As the latch passes over depressed lever No. 2 during the return of the carriage, the finger moves between the switch lugs without engaging any of them so that the control switch is not operated at this time.

Fig. 10 is a wiring diagram of a control switch 87 for operating a reversible electric motor 95 of a miniature railroad engine. The two circles represent opposite sides of the rotor 89, and pointers 97 and 98 rotate together, the former being connected to the positive side, and the latter to the negative side of a wiring system. The two rails of the miniature railroad system are indicated at 100 and 101. When the pointers are at the switch position A, the motor is stopped. When they are opposite the position B, the motor turns in one direction which is ahead for the engine, and when they are at the position C, the motor is stopped. When the pointers are at the point D the motor turns in the opposite direction to reverse the engine.

If the engine motor is the type that is reversed by changing the polarity of the current, the positions B and D of the control switch would both be go positions. The same applies if the apparatus is used to start and stop machinery.

Figure 11 diagrammatically illustrates the wiring for three selector units connected to the rails 100 and 101. A dial 105 of the type used on automatic telephones is also connected to the rails and is adapted to send out electric impulses over them. In the illustrated example, the number 1 on the dial is positioned to give 2 impulses, while the other numbers each give one impulse more than the previous number. This is necessary to allow for the No. 0 lever. If number 1 is dialled, the No. 1 levers of the three selector units are depressed, but there will be only one control switch operated, that is, the control switch which is located adjacent a No. 1 lever. If number 2 is dialled, the same thing happens excepting that the control switch at the No. 2 lever of one selector unit will be turned. The same thing applies when the number 3 is dialled. As the selector units are in different engines, the operator can control any one of the engines by dialling the number of that particular engine, said number corresponding to the number of its numbered lever having a control switch opposite it.

Figure 11 also shows a wiring set-up which may be used when the operating current flows through rails 100 and 101 to the engines. A source of electrical power 108 is directly connected to rail 101, and is connected to rail 100 through dial 105 and also through a power switch 109. When the dial is turned, electrical impulses are directed through the rails to the engines, but when switch 109 is closed by the operation, a steady current is directed to the engines and stops only when the switch is opened.

The operator selects the engine he wants to move by dialling its number to make the selection. Then he closes switch 109 to cause the engine to move in accordance with the selection. At this time, the carriages of all the selector units move forward one distance only and the latches thereof engage the shoulders of the No. 0 levers. These carriages do not return until the power switch is opened. The zero levers are depressed at this time but no control switch is operated. The zero levers are necessary to prevent the carriage from returning to its normal position immediately after the first impulse, when a number is dialled to operate a particular engine.

Figures 12 to 14 illustrate an alternative form of selector unit. As this unit functions in practically the same manner as the unit of Figure 1, it will not need a very detailed description.

5 This selector unit generally designated by the numeral 115 includes a vertical frame 117 having a carriage 118 slidably mounted along the upper edge thereof. This carriage is in the form of a bar suspended from rollers 120 which operate in a track 121 carried by the frame. 10 This carriage is formed with a rack 123 along its lower edge which meshes with a pinion 124 fixedly mounted on a shaft 125 carried by the frame. A ratchet wheel 127 is also fixedly mounted on this shaft adjacent the pinion and is engaged by a pawl 128 mounted on the end of a ratchet arm 130 which is pivotally mounted at 131 adjacent its opposite end on a bracket 132. A solenoid 134 has a movable plunger 135 which is connected at 136 at its outer end to the ratchet arm. A spring 137 is connected to the end of the ratchet arm near its pivot 131 20 and normally draws said end downwardly so as to keep the core 135 in its extended position. A helical spring 140 is fixedly mounted at its end 141 on the base of the frame, and its opposite end is connected to shaft 125. This spring tends to turn the shaft in a clockwise direction 25 (as viewed in Figure 12) and this moves the carriage to its normal rear position where it engages a stop 144.

When the solenoid 134 is subjected to an electric impulse, its core 135 is drawn downwardly to pivot the ratchet arm 130 in the same direction. Pawl 128 engages the ratchet wheel 127 to turn it a distance equal to that between two of its notches. This moves the carriage 118 forwardly on the frame.

The carriage has a latch 148 pivotally mounted on its rearward end and extending downwardly therefrom. 35 This latch is adapted to engage spaced and aligned levers 150 which are the same as levers 54 of the above form of the invention. These levers are also numbered 0 to 3 in order to correspond to the levers 54. A control switch 155 is positioned adjacent one of the levers 1 to 40 3 and has its lugs 156 projecting outwardly therefrom, one of which is always in line with the step of one of the levers which, in this case, is lever No. 1. A common bar 159 is connected to the lower ends of these levers and extends to a link 160 of a dashpot 161. A spring 162 tends to keep the levers in their uppermost positions. 45 The bar and levers form a carrier 164.

The alternative of Figures 12 to 14 operates in practically the same manner as the previously described selector unit. When the solenoid 134 is subjected to two electric impulses, carriage 118 is moved until its latch 148 engages No. 1 lever. If another impulse immediately follows this, the latch is moved until it engages No. 2 lever, the dashpot preventing spring 162 from returning the levers to their normal positions at this time, and also preventing the spring 140 from returning the carriage to its normal position. In this example, if there are two impulses, the control switch 155 is rotated, whereas if there are one, three or four impulses, the switch remains stationary. Thus, the control switch is operated in the 55 same manner as described above.

The alternative of Figures 15 to 17 is quite similar to the form of the invention illustrated in Figures 1 to 4, the main difference being in the form of the carrier. Carriage 22a is mounted and moved in the same manner 65 as carriage 22. However, in this example, a carrier 175 is substituted for carrier 72. The carrier 175 is in the form of a bar 177 below and extending parallel with the carriage, this bar having horizontal shoulders 178 extending along both sides thereof spaced below its upper edge. This upper edge has a plurality of notches therein forming shoulders 180 which are the equivalent of shoulders 57 of the previously-described levers 54. There is a shoulder 180 for each selector unit in the system, and in this example, there is an extra zero lever. These 70 shoulders are numbered 0, 1, 2 and 3 in the same manner 75

as the carrier levers. The carrier bar is supported by spaced vertical and parallel links 184 and 185. The bar is pivotally connected to the upper ends of these links, while the other ends of the latter are pivotally connected to the frame 11a. Link 184 has an extension 186 from its lower end which is pivotally connected to bar 60a at 187. The frame 11a is formed with a stop 188 against which the forward end of the carrier bar abuts when the links 184 and 185 are in vertical positions to which they are drawn by spring 70a.

There is a control switch 87a for each selector unit and in the illustrated example, there is always a lug 90a of this switch aligned with the No. 2 shoulder 180 of the carrier.

Carriage 22a has a latch 192 pivotally mounted at 193 on the rearward end thereof. This latch is in the form of spaced elongated side members 195, one on each side of the carriage, see Figure 17, having their upper ends projecting above the pivot 193 so that one of these ends is engaged by stop 144a when the carriage is in its normal at-rest position. At this time, the latch projects downwardly and rearwardly from the carriage, as clearly shown in Figure 15. A pin 198 extends through the side members 195 spaced upwardly from the lower ends thereof, and projects laterally from the latch. This pin is adapted to engage the lug 90a of the control switch in the same manner as the finger 76 of latch 74 engages lug 90 of Figures 1 to 4. The lower ends of the side members are preferably rounded as indicated at 199. A stop 200 is provided on the carriage near the latch 192 in order to hold the latter in a substantially vertical position when the carriage is moved away from stop 144a.

When the carriage 22a is moved forwardly by the electrical impulses in the manner described above, the side members 195 of latch 192 span the upper edge of the carrier bar 177. Pin 198 is so located that it rides along the upper edge of the bar and drops into the notches therein as the carriage progresses. After each impulse, the carriage tends to move rearwardly under the action of spring 28a, and the pin abuts against a shoulder 180 and starts to depress the carrier 175 against the action of spring 70a. As the dashpot 63a slows this action, the carriage does not move rearwardly very far unless the impulses stop.

If the number 2 is dialled, there are three electrical impulses as described above and the carriage moves until pin 198 of its latch engages No. 2 shoulder of the carrier, as shown in dotted lines in Figure 15. At this time the lateral extension of the pin engages the control switch lug 90a which is aligned with this shoulder. When the impulses stop, spring 28a draws the carriage rearwardly, causing latch 192 to pivot around its pin 193. This action causes the lower ends 199 of the latch side members to engage the horizontal shoulders 178 of the carrier bar. As the latch pin is bearing against a shoulder 180, the lower end of the latch cannot move rearwardly with the carriage so that the movement of the latch around the pivot 193 causes its lower end to depress the carrier, as shown in Figure 16. The carrier is depressed until the pin clears the shoulder, at which time the main part of the latch is in a substantially vertical position against stop 200. The latch keeps the carrier depressed until it clears the horizontal shoulders 178, after which spring 70a returns the carrier to its normal position ready for the next operation.

When the pin 198 engages the control switch lug 90a, the latter is moved to turn the switch to the next position thereof. This action moves another switch lug into line with No. 2 carrier shoulder.

If the carriage is moved under the influence of two impulses, the latch pin engages No. 1 shoulder, but the control switch of the illustrated selector unit is not operated. If there are four impulses, the latch pin engages No. 3 shoulder and when the latch is in the position shown in Figure 16, its pin 198 is high enough to clear the control

switch lug 90a so that the control switch is not operated as the latch moves rearwardly.

It is obvious that the selector unit of Figures 15 to 17 operates in the same manner as that of Figures 1 to 4, the only difference being that in the latter the carrier 72 consists of a plurality of levers 54 connected together by the bar 60 and having shoulders 57 at the upper ends of the levers, while in the former, carrier 175 comprises the bar 177 mounted on links 184 and 185 with the shoulders 180 along the upper edge of the bar. Furthermore, there is no reason why the carriage and operating mechanism therefor of Figures 12 to 14 may not be used with the carrier arrangement of Figures 15 to 17.

What I claim as my invention is:

15. A remote controlled selector unit comprising a carriage, means responsive to electric impulses for moving the carriage forwardly from a normal position a predetermined distance for each impulse, a plurality of spaced levers pivotally mounted adjacent the carriage, each lever having a shoulder thereon, resilient means normally maintaining the levers in initial positions, said levers being compressible against the action of the resilient means thereof, latch means on the carriage for successively engaging the lever shoulders as said carriage moves forwardly, each impulse causing the latch means to engage a different lever shoulder, and means for returning the carriage to its normal position when the impulses cease, said latch means depressing the lever it is in engagement with against the resilient means thereof after each impulse as the carriage is moved towards the normal position thereof, the resilient means of each lever retarding the movement of the carriage while the latch of the latter is depressing said lever.
20. A selector unit as claimed in claim 1 including means connecting the levers together whereby depression of one lever results in the depression of all of them.
25. A selector unit as claimed in claim 2 including means connected to the levers for slowing down the return thereof to their initial positions by the resilient means.
30. A selector unit as claimed in claim 2 including a control switch adjacent one of the levers engaged by the latch means as the latter engages the shoulder of said lever, said switch being operated by the latch means only when it depresses said lever.
35. A remote controlled selector unit comprising a carriage, means responsive to electric impulses for moving the carriage forwardly from a normal position a predetermined distance for each impulse, a plurality of spaced levers pivotally mounted adjacent the carriage, each lever having a shoulder thereon, latch means on the carriage for successively engaging the lever shoulders as said carriage moves forwardly, each impulse causing the latch means to engage a different lever shoulder, means connected to the carriage for moving it towards the normal position after each impulse, means for slowing down the return movement of the carriage, and a control switch adjacent one of the levers, said latch means engaging the switch when it engages the shoulder of the lever adjacent said switch, and said latch means depressing the lever it is in engagement with after the last impulse as the carriage is returned to the normal position and operating the switch if this lever is the one adjacent said switch.
40. A remote controlled selector unit comprising a frame, a carriage slidably mounted on the frame, ratchet teeth on the carriage extending longitudinally thereof, a ratchet arm pivotally mounted near the carriage and having a pawl positioned to engage the ratchet teeth, means connected to the arm for holding it in a normal position, means engaging the pawl when the arm is in the normal position to disengage the pawl from the carriage teeth, means responsive to electric impulses for moving the ratchet arm out of its normal position during each impulse, said pawl engaging one of the ratchet teeth 45 when the arm is moved to move the carriage with it,
45. A selector unit as claimed in claim 1 including means connecting the levers together whereby depression of one lever results in the depression of all of them.
50. A selector unit as claimed in claim 2 including means connected to the levers for slowing down the return thereof to their initial positions by the resilient means.
55. A selector unit as claimed in claim 2 including a control switch adjacent one of the levers engaged by the latch means as the latter engages the shoulder of said lever, said switch being operated by the latch means only when it depresses said lever.
60. A remote controlled selector unit comprising a carriage, means responsive to electric impulses for moving the carriage forwardly from a normal position a predetermined distance for each impulse, a plurality of spaced levers pivotally mounted adjacent the carriage, each lever having a shoulder thereon, latch means on the carriage for successively engaging the lever shoulders as said carriage moves forwardly, each impulse causing the latch means to engage a different lever shoulder, means connected to the carriage for moving it towards the normal position after each impulse, means for slowing down the return movement of the carriage, and a control switch adjacent one of the levers, said latch means engaging the switch when it engages the shoulder of the lever adjacent said switch, and said latch means depressing the lever it is in engagement with after the last impulse as the carriage is returned to the normal position and operating the switch if this lever is the one adjacent said switch.
65. A remote controlled selector unit comprising a frame, a carriage slidably mounted on the frame, ratchet teeth on the carriage extending longitudinally thereof, a ratchet arm pivotally mounted near the carriage and having a pawl positioned to engage the ratchet teeth, means connected to the arm for holding it in a normal position, means engaging the pawl when the arm is in the normal position to disengage the pawl from the carriage teeth, means responsive to electric impulses for moving the ratchet arm out of its normal position during each impulse, said pawl engaging one of the ratchet teeth 70 when the arm is moved to move the carriage with it,
75. A selector unit as claimed in claim 1 including means connecting the levers together whereby depression of one lever results in the depression of all of them.

means connected to the carriage for returning it to a normal position when the pawl is out of engagement with the teeth thereof, a plurality of spaced levers pivotally mounted adjacent the carriage, each lever having a shoulder thereon, resilient means normally retaining the levers in initial positions, said levers being depressible against the action of the resilient means thereof, latch means on the carriage for successively engaging the lever shoulders as said carriage moves forwardly, each impulse causing the latch means to engage a different lever shoulder, and said latch means depressing the lever it is in engagement with against the resilient means thereof after each impulse as the carriage is moved towards the normal position thereof, the resilient means of each lever retarding the movement of the carriage while the latch of the latter is depressing said lever.

7. A remote controlled selector unit comprising a frame, a carriage slidably mounted on the frame, ratchet teeth on the carriage extending longitudinally thereof, a ratchet arm pivotally mounted near the carriage and having a pawl positioned to engage the ratchet teeth, means connected to the arm for holding it in a normal position, means engaging the pawl when the arm is in the normal position to disengage the pawl from the carriage teeth, means responsive to electric impulses for moving the ratchet arm out of its normal position during each impulse, said pawl engaging one of the ratchet teeth when the arm is moved to move the carriage with it, means connected to the carriage for returning it to a normal position when the pawl is out of engagement with the teeth thereof, a plurality of spaced levers pivotally mounted adjacent the carriage, each lever having a shoulder thereon, latch means on the carriage for successively engaging the lever shoulders as said carriage moves forwardly, each impulse causing the latch means to engage a different lever shoulder, means for slowing down the return movement of the carriage, and a control switch adjacent one of the levers, said latch means engaging the switch when it engages the shoulder of the lever adjacent said switch, and said latch means depressing the lever it is in engagement with after the last impulse as the carriage is returned to the normal position and operating the switch if this lever is the one adjacent said switch.

8. A remote controlled selector unit comprising a frame, a carriage slidably mounted on the frame, ratchet teeth on the carriage extending longitudinally thereof, a pinion meshing with the rack teeth, a ratchet wheel mounted for rotation with the pinion, a ratchet arm pivotally mounted near the carriage and having a pawl positioned to engage the ratchet wheel, means connected to the arm for holding it in a normal position with the pawl clear of the ratchet wheel, a spring connected to the ratchet wheel tending to rotate it and move the carriage back to a normal position when the pawl is free of the ratchet wheel, means responsive to electric impulses for moving the ratchet arm out of its normal position during each impulse, said pawl engaging a tooth of the ratchet wheel when the arm is moved to rotate said wheel and move the carriage a predetermined distance for each impulse, a plurality of spaced levers pivotally mounted adjacent the carriage, each lever having a shoulder thereon, resilient means normally retaining the levers in initial positions, said levers being depressible against the action of the resilient means thereof, latch means on the carriage for successively engaging the lever shoulders as said carriage moves forwardly, each impulse causing the latch means to engage a different lever shoulder and said latch means depressing the lever it is in engagement with against the resilient means thereof after each impulse as the carriage is moved towards the normal position thereof, the resilient means of each lever retarding the movement of the carriage while the latch of the latter is depressing said lever.

9. A remote controlled selector unit comprising a

frame, a carriage slidably mounted on the frame, ratchet teeth on the carriage extending longitudinally thereof, a pinion meshing with the ratchet teeth, a ratchet wheel mounted for rotation with the pinion, a ratchet arm pivotally mounted near the carriage and having a pawl positioned to engage the ratchet wheel, means connected to the arm for holding it in a normal position with the pawl clear of the ratchet wheel, a spring connected to the ratchet wheel tending to rotate it and move the carriage back to a normal position, means responsive to electric impulses for moving the ratchet arm out of its normal position during each impulse, said pawl engaging a tooth of the ratchet wheel when the arm is moved to rotate said wheel and move the carriage a predetermined distance for each impulse, means connected to the carriage for returning it to a normal position when the pawl is free of the ratchet wheel, a plurality of spaced levers pivotally mounted adjacent the carriage, each lever having a shoulder thereon, latch means on the carriage for successively engaging the lever shoulders as said carriage moves forwardly, each impulse causing the latch means to engage a different lever shoulder, means for slowing down the return movement of the carriage, and a control switch adjacent one of the levers, said latch means engaging the switch when it engages the shoulder of the lever adjacent said switch, and said latch means depressing the lever it is in engagement with after the last impulse as the carriage is returned to the normal position and operating the switch if this lever is the one adjacent said switch.

10. A remote controlled selector unit comprising a carriage, means responsive to electric impulses for moving the carriage forwardly from a normal position a predetermined distance for each impulse, a carrier mounted near and parallel to the carriage, said carrier being movable from and back to an initial position, resilient means connected to the carrier to move said carrier back to the initial position after being moved therefrom, a plurality of spaced shoulders projecting outwardly from the carrier adjacent the carriage, said shoulders being depressed when the carrier is moved away from the initial position, latch means on the carriage for successively engaging the carrier shoulder as said carriage moves forwardly, each impulse causing the latch means to engage a different shoulder, and means continuously urging the carriage towards its normal position, said latch means when the carriage moves towards the normal position after each impulse engaging a carrier shoulder and tending to depress said shoulder to move the carrier away from the initial position against the resilient moving means thereof, said resilient moving means retarding the movement of the carriage towards the normal position, and when the impulses cease said carriage returning to the normal position after the latch means depresses the last shoulder engaged thereby.

11. A selector unit as claimed in claim 10 including means connected to the carrier for slowing down the return thereof to its initial position by the resilient moving means.

12. A remote controlled selector unit comprising a carriage, means responsive to electric impulses for moving the carriage forwardly from a normal position a predetermined distance for each impulse, a carrier bar mounted near and parallel to the carriage, said carrier bar being depressible from an initial position, resilient means connected to the carrier bar to move said bar back to the initial position after being moved therefrom, a plurality of spaced shoulders projecting outwardly from an edge of the bar near the carriage, a shoulder extending longitudinally of the bar spaced from the other shoulders thereof, a latch pivotally mounted near one end of the carriage normally clear of the carrier shoulders, a pin on the latch spaced from the opposite end thereof for successively engaging the shoulders as the carriage moves forwardly, each impulse causing the latch pin to engage

75

a different shoulder, and means continuously urging the carriage towards its normal position, said latch pin after each impulse engaging one of the spaced carrier shoulders during movement of the carriage towards the normal position to swing the latch to cause said opposite end thereof to engage the longitudinal shoulder of the carrier and depress the carrier against the action of the resilient means, said resilient means retarding the movement of the carriage towards the normal position while the latch pin is in engagement with a carrier shoulder.

13. A selector unit as claimed in claim 12 including means for retarding the movement of the carrier by the resilient means.

14. A remote controlled selector unit comprising a carriage, means responsive to electric impulses for moving the carriage forwardly from a normal position a predetermined distance for each impulse, a carrier mounted near and parallel to the carriage, said carrier being movable from and back to an initial position, resilient means connected to the carrier to move said carrier back to the initial position after being moved therefrom, a plurality of spaced shoulders projecting outwardly from the carrier adjacent the carriage, said shoulders being depressed when the carrier is moved away from the initial position, latch means on the carriage for successively engaging the carrier shoulder as said carriage moves forwardly, each impulse causing the latch means to engage a different shoulder, means continuously urging the carriage towards its normal position, said latch means when the carriage moves towards the normal position after each impulse engaging a carrier shoulder and tending to depress said shoulder to move the carrier away from the initial position against the resilient moving means thereof, said resilient moving means retarding the movement of the carriage towards the normal position, and when the impulses cease said carriage returning to the normal position after the latch means depresses the last shoulder engaged thereby and switch means adjacent one of the shoulders, said switch means being engaged by the latch means when the latter engages the adjacent shoulder and being operated when the latch means depresses said shoulder.

15. A remote controlled selector unit comprising a carriage, means responsive to electric impulses for moving the carriage forwardly from a normal position a predetermined distance for each impulse, a plurality of spaced and interconnected shoulders mounted near and parallel to the carriage, resilient means normally maintaining the shoulders in an initial position, said shoulders being depressible against the action of the resilient means thereof, latch means on the carriage for successively engaging the shoulders as said carriage moves forwardly, each impulse causing the latch means to engage a different shoulder, and means continuously urging the carriage towards its normal position, said latch means when the carriage moves towards the normal position after each impulse engaging and tending to depress a shoulder to move the shoulders away from the initial position against the resilient moving means thereof, said resilient moving means retarding the movement of the carriage towards the normal position, and when the impulses cease said carriage returning to the normal position after the latch means depresses the last shoulder engaged thereby.

16. A remote controlled selector unit comprising a carriage, means responsive to electric impulses for moving the carriage forwardly from a normal position a predetermined distance for each impulse, a plurality of spaced and interconnected shoulders mounted near and parallel

to the carriage, resilient means normally maintaining the shoulders in an initial position, said shoulders being depressible against the action of the resilient means thereof, latch means on the carriage for successively engaging the shoulders as said carriage moves forwardly, each impulse causing the latch means to engage a different shoulder, means continuously urging the carriage towards its normal position, said latch means when the carriage moves towards the normal position after each impulse engaging and tending to depress a shoulder to move the shoulders away from the initial position against the resilient moving means thereof, said resilient moving means retarding the movement of the carriage towards the normal position, and when the impulses cease said carriage returning to the normal position after the latch means depresses the last shoulder engaged thereby, and switch means adjacent one of the shoulders, said switch means being engaged by the latch means when the latter engages the adjacent shoulder and being operated when the latch means depresses said shoulder.

17. In control apparatus, a plurality of selector units; each unit comprising a carriage, means responsive to electric impulses for moving the carriage forwardly from a normal position a predetermined distance for each impulse, a carrier mounted near and parallel to the carriage, said carrier being movable from and back to an initial position, resilient means connected to the carrier to move said carrier back to the initial position after being moved therefrom, a plurality of spaced shoulders projecting outwardly from the carrier adjacent the carriage, said shoulders being depressed when the carrier is moved away from the initial position, there being one shoulder for each selector unit in the apparatus, latch means on the carriage for successively engaging the carrier shoulder as said carriage moves forwardly, each impulse causing the latch means to engage a different shoulder, means continuously urging the carriage towards its normal position, said latch means when the carriage moves towards the normal position after each impulse engaging a carrier shoulder and tending to depress said shoulder to move the carrier away from the initial position against the resilient moving means thereof, said resilient moving means retarding the movement of the carriage towards the normal position, and when the impulses cease said carriage returning to the normal position after the latch means depresses the last shoulder engaged thereby, and a control switch adjacent one of the shoulders, said latch engaging the switch when it engages the shoulder adjacent said switch; the shoulders in each selector unit corresponding to those in the other units and the control switch of each unit being near a different shoulder from the shoulders of all the other units.
